United States Patent Office

Des. 193,381
Patented Aug. 14, 1962

193,381

AUDIO COMMUNICATION HAT

Warren R. Churchill, Franklin, Tenn., assignor to
Kusan Incorporated, Nashville, Tenn.

Filed June 29, 1961, Ser. No. 65,765

Term of patent 3½ years

(Cl. D3—13)

FIG. 3

FIG. 1 is a $\frac{3}{4}$ perspective view of an audio communication hat showing my new design.

FIG. 2 is a $\frac{3}{4}$ rear perspective view thereof, and

FIG. 3 is a front elevational view thereof.

I claim:

The ornamental design for an audio communication hat, as shown.
